UNITED STATES PATENT OFFICE.

HERRMAN J. BACHRAN, OF NEW YORK, N. Y.

CIGAR-BUNCHING MACHINE.

SPECIFICATION forming part of Letters Patent No. 366,062, dated July 5, 1887.

Application filed March 28, 1885. Serial No. 160,415. (No model.)

To all whom it may concern:

Be it known that I, HERRMAN J. BACHRAN, a citizen of the United States, residing in the city, county, and State of New York, have invented certain new and useful Improvements in Cigar-Bunching Machines, of which the following is a full and complete description, reference being had to the accompanying drawings, which for a part of this specification.

10 My invention relates to that class of machines used for rolling or bunching the fillers of cigars, and my object is to provide a machine capable of working long fillers; and to this end my invention consists in certain constructions, combinations, and arrangements of parts, as will be hereinafter fully described, and pointed out in the claims.

15 In the accompanying drawings, Figure 1 represents a front elevation; Fig. 2, a plan view with the top frame and roller removed; Fig. 3 an end elevation, and Fig. 4 a transverse section, of a machine embodying my invention. Fig. 5 is an elevation of the gears on the rollers; Fig. 6, a detached view of the band-pulley and its pawl; Fig. 7, a sectional detail showing band-pulley and pawl, the ratchet-wheel, and the gear-wheel which imparts motion to the rollers; Fig. 8, a view of a modified form of roller; Fig. 9, a detached 20 view of rollers and belts; Fig. 10, a plan view of one of the belts, and Fig. 11 a section through the belt.

25 In carrying out my invention, I provide a rectangular frame, 1, of suitable dimensions, in which I mount three rollers, B C D, which are journaled in the ends of the frame, and are at one end provided with gear-wheels I J K, which mesh with and are driven by a central gear-wheel, i, which is mounted on a shaft, 30 T, one end of which is journaled in the frame 1 and the other end in a post, L, which rises from an end projection at the bottom of the frame 1. The wheel i constitutes the drive-wheel by which the rollers B C D are rotated. 35 The rollers B C D carry one or more endless belts, M, which are sufficiently slack to form a pocket or trough between the rollers B C, as shown in Fig. 4, into which pocket is placed the tobacco to be rolled or bunched. The 40 binder is then slantingly placed on top of the tobacco, as shown in Fig. 1. The top of the machine is then shut down and the wheels set

in motion. To the top of the frame 1, at one side, is hinged a frame, 2, (see Figs. 3 and 4,) in which is journaled a roller, A, which has at 45 one end a gear-wheel, G, similar to the gear-wheels I J K, and which also meshes with the central gear, i, and is driven thereby. Fig. 5 illustrates the relative arrangement of the gears referred to. The roller A is vertically 50 above the pocket or trough above referred to, and the latter is of such depth that the roller will bear upon the bunch of tobacco, as shown in dotted lines in Fig. 4, and assist in rolling the same into symmetrical shape. 55

On the shaft T, which carries the gear-wheel i, are also mounted a band pulley or wheel, W, which carries a pawl, Z, (see Figs. 6 and 7,) and a ratchet-wheel, V, the latter and the gear-wheel i being rigidly mounted 60 on the shaft to turn therewith, while the wheel W is loosely mounted and is free to turn thereon in one direction, but is held against independent rotation in the opposite direction by the engagement of its pawl Z with the 65 ratchet-wheel V.

The belts M are of such width and thickness as may be necessary to form bunches of given length and thickness, and the machine is of such length as to carry any number of belts 70 desired. The drawings Figs. 1 and 2 show three; but a greater or less number may be used according to the capacity which it is desired to give the machine. The belts M are concaved in cross-section on their outer faces, the 75 concavity being such as will give to the bunch of tobacco the desired shape, and are flat on their inner faces to fit snugly against the carrying-rollers.

Fig. 10 represents one of the belts separate 80 from the rollers and stretched out to its full length. The curved lines at the ends show the concavity, and the dotted lines indicate the flat inner face. The upper roller, A, is hollowed out or reduced at points above the belts 85 M, the reduced parts corresponding in length and depth with the concavities in the belts, and act in conjunction therewith to roll the tobacco into bunches, as already explained. The upper frame, 2, which carries the roller 90 A, is hinged at 3 to the frame 1, so as to be capable of being raised or turned back, as shown in dotted lines in Fig. 3. This is for 95 the purpose of allowing the roller A to be 100

readily moved out of the way to permit tobacco to be placed in the machine and to be removed when properly rolled or bunched. The frame 2 is fastened down by hooks 4, or 5 equivalent fastening devices, which are unhooked when it is desired to raise the roller A. An arm, 5, on the frame carries a counter-weight, 6, which facilitates the raising of the frame and its roller A. The end of the frame 10 1 opposite the gears is removable for the purpose of allowing the belts and rollers, either or both, to be taken out and replaced. It is secured to the base by screws S, which pass through an out-turned flange at the bottom 15 and screw into the base of the frame. By removing the screws the end may be taken off.

As a means for driving the machine I show a foot-lever, 7, which is pivoted to a bracket or post, 8, and to this lever is attached one 20 end of a cord, 9, which passes over the wheel W and carries at its other end a weight, 10. When the lever is depressed by the foot of the operator, the cord is drawn over the wheel, causing the latter to turn in the direction indicated by the arrow in Fig. 3. The wheel W 25 being locked against independent forward rotation on its shaft by the engagement of its pawl with the ratchet-wheel V, the parts are all turned together and the wheel i imparts rotary motion to the rollers. When the lever 7 is released, the wheel W is turned backward on the shaft by the action of the weight and cord, the pawl Z riding over the teeth of the ratchet-wheel V, and the lever is drawn up to 30 its normal position ready for another operation. When the operation is complete, the top frame, 2, is turned back and the roller A moved out of the way, when the partially-finished cigar can be taken out of the machine 35 and a new supply of tobacco put in for the next operation.

When more than one belt is used, the different belts may be of different thicknesses or widths, to form different-sized bunches, and the 45 concavities in the different belts may be of different form to form different-shaped bunches at the same operation. A spring would evidently be the mechanical equivalent of the weight 10, and might be substituted therefor 50 without departing from the invention. So, also, a crank, to be turned by an assistant, might be substituted for the wheel W, the lever 7, the ratchet-wheel V, and the cord and weight; but I prefer the mechanism shown and described.

Having thus described my invention, I 55 claim—

1. In a cigar-bunching machine, the combination of four rollers arranged around and equidistant from a central point, the upper 60 roller being carried by a hinged frame, 2, and one or more belts passing around three of said rollers and sufficiently slack to form a trough or pocket to receive and hold the tobacco to be bunched below the fourth roller, substantially as and for the purpose described.

2. In a cigar-bunching machine, the combination of four rollers arranged around and equidistant from a central point, the upper roller being carried by a hinged frame, 2, and each having at one end a gear-wheel, one or 65 more belts passing around three of said rollers and sufficiently slack to form a pocket or trough to receive and hold the tobacco to be bunched below the fourth roller, and a central driving-gear which engages and drives the 70 gears of all the rollers, substantially as and for the purpose described.

3. In a cigar-bunch-making machine, the combination of the frame 1, the three rollers mounted therein and provided at one end with 80 gears I J K, one or more endless belts passing around said rollers and sufficiently slack to form a trough or pocket between the rollers B C to receive and hold the tobacco to be bunched, a frame, 2, hinged at one side to the frame 1, 85 and carrying a roller, A, with a gear, G, at one end, and a central drive-gear which meshes with all the gears and drives them, substantially as shown and described.

4. In a cigar-machine, the combination of a series of rollers provided with gears at one end and carrying one or more belts, M, a central shaft, T, carrying a drive-gear, i, which meshes with the gears of all the rollers, and a band-wheel, W, carrying a pawl, Z, and ratchet-wheel V, with which the pawl engages, the gear i and the ratchet-wheel V being rigidly secured upon the shaft, and the band-wheel W loosely mounted thereon, a foot-lever, 7, a cord, 9, attached to said lever and passing over the wheel W, and a weight, 10, or its equivalent, attached to the cord, substantially as shown and described.

5. In a cigar-machine, the combination, with a series of rollers and one or more concave-faced belts carried thereby, of a main stationary frame which supports one end of said rollers and their driving-gear, and a removable frame or support for supporting the opposite ends, whereby provision is made for removing or changing the belts without opening or cutting the same.

6. In a cigar-machine, the combination of a series of rollers, B C D, one or more concave-faced belts mounted thereon and sufficiently slack to form a trough or pocket between the side rollers, B C, and a roller, A, above said trough or pocket, and having one or more reduced portions which correspond in longitudinal outline with the concavities of the belts, substantially as and for the purpose described.

In testimony whereof I hereunto set my hand in presence of two witnesses.

HERRMAN J. BACHRAN.
